APPARATUS FOR PRODUCING CELLULAR
CONCRETEJohn A. Rice, Berkeley, Calif., assignor to The
Bubblestone Company, Pittsburgh, Pa., a cor-
poration of Pennsylvania

Application October 18, 1935, Serial No. 45,684

4 Claims. (Cl. 83-151)

The present invention relates to a method of and apparatus for producing cellular concrete and consists in the novel steps of procedure, and combinations and arrangements of elements of apparatus hereinafter described and particularly set forth in the accompanying claims.

The disclosure herein forms a continuation in part of my co-pending application for U. S. Patent on Process and apparatus for making acoustic material and foaming compounds, filed April 27, 1931, Serial No. 533,351, and of which parent application there is filed of even date a divisional application for patent on "Acoustic material and process of producing the same", Serial No. 45,685, filed October 18, 1935.

The method phase of the invention consists essentially in combining a cement slurry with a suitable foaming compound and then aerating the mixture by mechanically beating or incorporating therein the films of air by means of foraminous or perforated sheets, e. g. screens, that enter the material carrying entrained air which thereafter forms into bubbles that harden and produce a cellular product.

The apparatus is characterized in that it embodies a plurality of arcuate or cylindrical-like sections of screen or perforated material spirally arranged on a common rotatable shaft, which in operation serve to drag films of entrailing air into the mixture of slurry and foaming solution, and simultaneously therewith agitate the mass to thoroughly distribute the created bubbles thus obtaining a uniformly cellular structure.

The invention is shown by way of illustration in the accompanying drawings wherein:

Figure 1 is a vertical sectional view of the machine,

Figure 2 a central sectional view thereof taken on the line 2—2 of Figure 1.

Figure 3, a central sectional view showing a modified form in which quarter spirals are used.

Figure 4, a similar view having one complete spiral.

Figure 5, an embodiment in which only a portion of a spiral is employed, and;

Figure 6, a further embodiment disclosing one continuous spiral of four convolutions.

Referring to the construction in further detail, the apparatus consists of a series of arcuate or cylindrical shaped sections 10, 11, 12, 13, 14, 15, 16, and 17, formed of screen, wire cloth, expanded or punched sheet metal or other similar material, arranged in spiral like form on the rotary shaft 18, said shaft being journaled on bearings 19 and 20 within a suitably shaped container 21

having discharge outlet 38. There are appreciably wide and open spaces, 22, 23, 24, 25, 26, 27, 28, and 29 between said screen members, and at 30, 31, 32, 33, 34, 35, 36, and 37 are stops or barriers, also made of the same or similar material as the screen members. The cement and water, with or without aggregate forming a thin slurry, (usually in an auxiliary slurry mixer), are poured into the container 21, approximately sufficient to fill the same up to the level of the dotted line 10 f.f. Sufficient foam compound is then introduced into the machine, and immediately becomes mixed with the slurry giving the same a foamy character,—that is to say,—making it to be of a foamy nature.

The screen members, after initially passing through the slurry, will become coated with numerous thin films, and thereafter when the spaces between the turns of the screens are submerged in the slurry, numerous air cells will be formed by the discharge of entrapped air into the slurry through the meshes of the screens. Upon emergence from the slurry, the closed spaces between the screens will again become largely filled with air when the slurry flows out by gravity, and the operation will be repeated during each revolution of the shaft. The spiral principle is believed the most suitable for handling slurries of all kinds such as Portland cement, gypsum, clay, all thick solutions, and mixtures of liquids and solids in which it is desired to incorporate a cellular structure by means of gas bubbles.

In the modified construction shown in Figure 3 there are four arcuate sections 39 disposed in spiral relation providing spaces 41 between the adjacent ends thereof through which the mixture enters. The screen 42 in Figure 4 is in one piece forming a complete spiral having an opening 43 for the material. In Figure 5 the screen 44 is in one piece arranged spirally for approximately one-third the circumference of the disks 40, and its trailing end is spaced from the edge of disks 40 to provide an entrance opening 45. The screen 46 in Figure 6 is in one piece and of a length 40 to form four complete convolutions having an entrance opening 47 between its leading end and the adjacent convolution.

The function of the barriers or stop members 31 to 37 is to impede the flow of slurry along the spiral channels between the screen members and to form closed spaces when the meshes are filled with films, thus carrying the maximum volume of air deeply into the slurry and giving efficiency to the machine. The use of these stops 50 55

or barriers increase the output of the machine to an extent appreciably greater than if they were not used. The several sections 10-17 are assembled in such angular relation that the respective front or advancing edges thereof are uniformly located about the circumference of the tank, and the barriers or baffles 30-37 are similarly arranged, all to the end of even distribution of load on the machine during working as will be understood. Continued operation of the machine as described will finally use up the available water of the slurry, forming air cells each with a surrounding film of water containing a minute quantity of foaming compound. Thus the aeration will cease when no more water is available, and the slurry will cease to expand in volume as a consequence. If more water is added and the machine operated, the slurry will further increase in volume due to additional films being formed with air entrapped therein.

A suitable mixture is:

Water _____ gallons 8.5
Sand (finer than 50 mesh to the inch)
25 Cement _____ cubic foot 1
Foaming Compound _____ pounds (1 sack) 94
Cement _____ ounces 7
(Sand should be finer than 50 mesh and coarser than 100 mesh.)

30 When aerated, this mixture will have a volume of approximately six cubic feet, weighing approximately forty-five (45) pounds to the cubic foot. Mixtures of heavier or lighter weight to the cubic foot may be made by correspondingly decreasing 35 or increasing the amount of water used thus increasing or decreasing the proportion of air cells in the batch. Different kinds of materials may obviously be used e. g. concrete, portland cement, gypsum, clay, or other cementitious substances, and it is preferred to combine the cement slurry with the foaming compound and then to aerate the mixture as explained.

By varying the character of the compound, the

cells may be caused to break thereby forming a porous like product which may be used for acoustical purposes, but it will be understood the breaking of the bubbles is not the function or purpose of the machine.

It will be understood the invention as herein disclosed is not limited to the details of construction shown and described as these may be varied widely without departing from the spirit of the invention except as defined by the claims.

What is claimed as new is:

1. An apparatus of the character described comprising a slurry mixture tank, a shaft journaled therein, a plurality of arcuate members of foraminous material mounted in angularly spaced relation on said shaft, and a plurality of radially disposed foraminous members associated with said arcuate members and cooperable therewith to dip into the slurry mixture and emerge therefrom whereby to cause entrapping of air bubbles therein, as and for the purpose set forth. 15

2. In an aerating device as in claim 1 foraminous partitions arranged across the spiral-cylindrical members, and dividing the same into a plurality of compartments to increase the air entrapping effect. 25

3. In an aerating device as in claim 1 substantially radial foraminous partitions arranged across the spiral-cylindrical members dividing the same into a plurality of compartments to increase the air entrapping effect. 30

4. An apparatus of the character described comprising a slurry mixture tank, a shaft journaled therein, a plurality of spiral-like members of foraminous material mounted on the shaft in angularly spaced relation, and a plurality of foraminous members radially intersecting said arcuate foraminous members and cooperable therewith to dip into the slurry mixture and emerge therefrom whereby to cause entrapping of air bubbles therein, as and for the purpose set forth. 40

JOHN A. RICE.
